APRON

Gertrude Fox Rider, 304 NE. Russell St., Portland, Oreg.

Filed July 25, 1960, Ser. No. 61,504

Term of patent 14 years

(Cl. D3—26)

The figure on the drawing is a front elevational view of an apron showing my new design. The back thereof follows along similar lines and the wide portions of the belt are set into the body of the apron.

I claim:

The ornamental design for an apron, substantially as shown and described.
